UNITED STATES PATENT OFFICE.

HENRY WARD DARROW, OF CHICAGO, ILLINOIS, ASSIGNOR, BY MESNE ASSIGNMENTS,
TO FRITZ MUSER, OF NEW YORK, N. Y.

CYLINDER WASHING-MACHINE.

1,077,043.

Specification of Letters Patent.

Patented Oct. 28, 1913.

Application filed December 7, 1908. Serial No. 466,336.

To all whom it may concern:

Be it known that I, HENRY WARD DARROW, a citizen of the United States, residing at Chicago, in the county of Cook and State of Illinois, have invented certain new and useful Improvements in Cylinder Washing-Machines, of which the following is a specification.

My invention relates in general to washing machines, and more particularly to the type known as cylinder-washing machines.

My invention has for its objects to produce a washing machine which will be thoroughly sanitary, and to fully accomplish this the machine is preferably made entirely of metal, the use of wood being eliminated; to provide a supporting frame which will be strong and rigid, and at the same time of simple construction; to so design certain members of the supporting frame that they will afford means for securely supporting a motor and driving mechanism, as well as contribute to the strength of the machine; to provide facilities for easily introducing and removing the articles; to so construct the machine that the articles will be thoroughly cleansed without injury; and to provide for the substantial support of a clothes wringer in convenient position to receive the articles as they are removed from the cylinder.

My invention has for its general object the production of a washing machine which will be simple in construction, inexpensive in manufacture, efficient in operation and durable in use.

My invention will be more fully described hereinafter with reference to the accompanying drawings, in which the same is illustrated and embodied in a convenient and practical form, and in which

Figure 1 is a vertical section of the machine, taken on the line 1 in Fig. 3, looking in the direction of the arrow, and further shows the position assumed by the drum relative to the casing in dotted lines. Fig. 1^a is a detail horizontal section taken on the line 1^a in Fig. 1 looking in the direction of the arrow. Fig. 2 is a vertical section of the machine, taken on the line 2 in Fig. 3, looking in the direction of the arrow. Fig. 3 is a top plan view, the cover being removed and certain other parts being broken away. Figs. 4, 5 and 6 are perspective views in de-

tail of cross braces of the structure. Fig. 7 55 is a horizontal section on the line 7 of Fig. 2, looking in the direction of the arrow. Fig. 8 is a perspective view in detail of one of the corner pieces, and Fig. 9 is a section on the line 9 of Fig. 1, looking in the direction of the arrow.

In the particular embodiment of my invention which I have chosen to illustrate in the accompanying drawings, the machine as a whole is supported upon four corner posts, 65 each corner post consisting of an upper section 15 and a lower section 16 joined together by bolts 18 which pass through a tongue 17 that projects upward from the lower section 16 and lies within the angle of 70 the upper section 15. Detachable casters are provided for the lower ends of the corner posts, each caster consisting of a bracket 20 carrying the caster wheel 19 and being clamped in place by means of the ring 21. 75 Two corner posts 15 at one end of the machine are joined together by the horizontal transverse brace 22—23, this brace having an angular cross section with one flange 22 in a vertical plane and the other flange 23 80 in a horizontal plane. The motor 24 is attached to the under side of the horizontal flange 23. The horizontal brace 22—23 is attached to the corner posts 15 by means of stud bolts 25. Above the brace 22—23 and 85 parallel therewith is another brace 26 connecting the same two corner posts 15 and attached to them by means of the bolts 27. On the same level with the brace 26 and respectively on the front and back sides of 90 the machine are the two stiffening bars 28 seen in Figs. 1, 2 and 7. The left-hand ends of these bars are bent at right angles around the corners of the machine, as indicated by the reference numeral 29. The corner posts 95 15 are made with grooves to accommodate these ends 29.

At the two corners of the machine at the rear thereof, at the same height as the brace 26, are two small inside corner angle pieces 100 30. The right-hand ends of the stiffened members 28 stick under the corner posts 15, these being shaped to accommodate them, as indicated by the reference numeral 31. At the front of the machine, fitting the inside 105 corners thereof, are the two corner braces 32, as shown in Figs. 1, 2 7 and 8. Each of these corner braces consists of a main flange

32 which fits against the side wall of the washing machine tank and a flange 33 at a right angle thereto which fits against the front wall of the tank. The edge of the flange 32 has a guide lip 34 which ends in a hook 36 at the bottom; the purpose of this will be explained later. The lower part of the flange 32 is curved, as indicated by the reference numeral 35, to conform to the curvature of the bottom of the washing machine tank. At the same height as the brace 26, but on the opposite side of the machine frame is a horizontal brace 37 with its ends 38 projecting under the edges of corner posts 15 which are shaped to accommodate them.

The washing machine tank consists of a curved piece of sheet metal 39 having its front and rear ends respectively 40 and 41 bent up in parallel vertical planes. Attached to this curved sheet are the side sheets 42 and 43.

I will now proceed to describe the framework about the top edge of the washing machine.

At the front there is an inside edge plate 44 having a lip or flange 45 which rests upon the top edge of the sheet metal wall 40. This brace 44-45 extends the full inside width of the tank, its ends abutting against the respective side walls 42 and 43. Across the top edges of the sides 42 and 43 on the inner faces thereof are the two braces 46 and 47 and having their respective top flanges 48 and 49 extending above the top edges of the side walls. The upper edges of the corner braces 32 (Fig. 8) are drawn out to a thin edge, as indicated by the reference numeral 50, and this thin edge is slipped up under the ends of the front top brace 44-45 and the two side top braces 46 and 47. The portions of the front top brace 44-45 under which these corner braces 32 are introduced are indicated by the reference numeral 51. Across the inside top rear edge of the washing machine tank extends the plate 52 having a lower flange 53 and an upper flange 54, as shown in Figs. 1, 2 and 5. In the same position but just outside of the tank wall 41 is the plate 55, the two plates 52 and 55 being clamped together by means of screws 56.

On the rear left corner of the machine overlying the corner post 15 is the angular member 57 which is extended upward in a bracket 58-59 that carries a journal bearing for the shaft 60. This shaft 60 transmits power from the motor 24 through connections not shown in the drawings to the wringer 61. This wringer 61 has clamping jaws 62 and 63 which carry thumb screws 64 adapted to engage the rear top edge plates 52 and 55.

The right-hand side wall of the machine has a casting 65 attached to the inner side

thereof. This casting is shown in dotted lines in Fig. 2 and it has a flange 66 which is formed as shown to make a socket for the trunnion 67. This casting is attached to the side wall 42 by means of screws 68.

Attached to the inside of the left-hand side wall 43 is the extended plate 69, the upper end 70 of which projects under the offset portion 71 of the top edge brace 46. The front edge of this casting is thickened as indicated by the reference numeral 69' and carries a flange 70' which is shaped to form a socket for the trunnion 71'. The rear end of the plate 69 is indicated by the reference numeral 72 and it abuts against the rear wall 41 of the washing machine tank, being secured to the corner post 15 and the overlying corner brace 57 by means of stud bolts 73. The gear wheel 74 is mounted on a shaft which projects through the left-hand side wall 43 of the washing machine tank. There are driving connections from the motor 24 to the rotating gear wheel 74, but these are not shown in the drawings. A plate 75 is pivotally mounted upon the shaft of the gear wheel 74, but its oscillatory movement about said shaft is limited by the pin 77 engaging the slot 76. A projecting lip 78 from the plate 69 overhangs the oscillatory plate 75. The idler wheel 79 in engagement with the gear wheel 74 is mounted on the oscillatory plate 75 and communicates rotation from the gear wheel 74 to another gear wheel 80 on the same plate 75. The teeth of this gear wheel 80 are in engagement with the circumferential series of studs 81 on the end of the drum 94. These studs 81 are carried by a spider 82, which also carries the trunnion 71'. It will be seen that the washing drum 94 is supported by the two trunnions 67 and 71'. The rod 83 has one end pivotally connected to the oscillatory plate 75, the other end of the rod 83 passing through holes 84 in the flange 70' just above the trunnion 71'.

The side top braces 46 and 47 have inside flanges 85 which are adapted to support the washing machine cover. These flanges are interrupted at an intermediate point of each, as indicated by the reference numeral 86, these gaps being intended to afford a passage for the trunnions 67 and 71' whenever it may be desired to lift the washing drum 94 in or out with respect to the washing machine tank. At the front ends of the flanges 85 are the studs 87, and extending downward from these studs 87 are short flanges 88 which form continuations of the lips or flanges 34 of the corner braces 32. The cover 89 is shown in closed position in Fig. 2 and in open position in Fig. 1. Its front and rear edges are rolled over, as indicated at 90, and on its side edges are the folded braces 91. At the front ends are 12a

sockets 92 with gaps 93 therein for a purpose which will be stated later and which is illustrated in Fig. 1.

The drum 94 has a reversely curved flexible sheet metal cover 97 pivoted along the longitudinal axis 95. The opening which is adapted to be closed by this cover 97 is formed at the sides by edge plates 96 which have their ends bent aside as indicated by the reference numeral 101. The edges of the drum 94 adjacent to the opening are rolled over, as indicated by the reference numeral 99, and the free edge of the cover 97 is similarly rolled over as indicated by the reference numeral 100. Attached to the inside face of the cover 97 is the longitudinally corrugated sheet metal plate 102. The outside handles 103 each have one end 105 firmly attached to the cover 97, but the other end 104 passes loosely through a hole in the cover 97.

At the rear ends of the top side braces 46 and 47 the studs 106 project inwardly. The sheet metal cover 110 has its rear edge rolled around these studs 106, as indicated by the reference numeral 107; thus the studs 106 form pivotal supports for the cover 110. Lugs 108 and 109 project inwardly from the braces 46 and 47 and form supports for the lateral edges of the hinged cover 110. Its free edge 111 is rolled over as shown in Figs. 1 and 2, and when the covers are in closed position, the edge 90 of the cover 89 overlaps the edge 111 of the cover 110. There is a series of holes 112 along the cover 110 and there is a space 113 between the rear edge of the cover 110 and the rear wall 41 of the washing machine tank.

Within the drum 94 of the washing machine are two longitudinal baffles 114 supported at their ends by the end plates 115 and having their edges rolled over as at 116. These baffles 114 are both disposed on one side of the axis of the drum 94. The concrete wall of the drum 94 has numerous perforations 117.

The nature of the joint between the walls 39, 41 and 43 of the washing machine tank is indicated by the reference numeral 118 in Fig. 9.

A drainage outlet 119 is provided for the tank, as shown in Fig. 2.

Assuming that the washing machine has the top covers all closed, as shown in Fig. 2, and that it is desired to open it up, the top cover 89 may be rotated up about its front edge 90 as an axis. Thus when the cover 89 has reached a substantially vertical position, it will slide down inside the front wall 40 of the washing machine tank having its lateral edges guided by the flanges 34 on the corner braces 32; finally, the front edge 90 of the cover will rest on the lower ends 36 of the flanges 34; the cover 89 will then be in the position shown

in Fig. 1. Thereafter the drum 94 will be rotated on its trunnions 71' and 67 until the opening in the top thereof takes the position shown in dotted lines in Fig. 1. Then (referring to Fig. 2) a downward pressure on the handles 103 will push the ends 104 down, thus increasing the flexure of the cover 97 and thereby withdrawing the edge 100 of the cover 97 from under the edge 99 of the drum 94. Thereafter the cover 97 will be rotated about the axis 95 until it assumes the position shown in dotted lines in Fig. 1, the ends of the rolled edge 100 being passed through the gaps 93 into the sockets 92 carried by the cover plate 89.

Numerous advantages are secured by this arrangement of the parts, among which may be mentioned the following: In all positions, whether opened or closed, the cover plate 89 is above the washing machine tank and when the cover is opened back and dropped down into the position shown in Fig. 1, it is still within the tank so that all dripping of water from the tank to the floor is avoided. In removing clothing from the drum 94 through the opening therein, it is desirable that the drum should be held against rotation on its trunnions 71' and 67. This is effectively accomplished by locking the edge of the hinged drum cover 97 into the sockets 92. Occasionally it may be found desirable to rub certain articles of clothing more or less when removing them from the washing machine drum 94. The corrugated sheet 102 is provided for this purpose, and as will be seen from an inspection of Fig. 1, it is held in a convenient position and is immovably supported.

It will be seen that when the parts are in the position shown in Fig. 1, the clothing may be readily passed through the wringer 61 as it is lifted out from the drum 94. The drip from the wringer will fall down upon the auxiliary cover 110 and will pass down through the holes 112 thereof and through the space 113 at the rear edge. When it is desired to lift the drum 94 out from the tank, the wringer 61 must first be removed by loosening the thumb screw 64; then the hinged cover 110 can be thrown back against the rear edge 54 of the tank and the drum 94 can be lifted out, the trunnions 71' and 67 passing up through the openings 86 in the flanges 85.

I have found that the disposition of the baffles 114 in the drum 94 is especially advantageous in thoroughly cleansing the clothes.

The arrangement of the gear studs 81 on the end of the drum, as shown in Fig. 1, is known in the prior art and is not here claimed. The driving pinion 80 is shown in Fig. 1 in engagement with the studs 81 on the inside thereof, but the oscillatory plate 75 permits the pinion 80 after having

4 turned the drum 94 through substantially one complete revolution to shift to the outside of the studs 81, thus reversing the direction of movement of the drum 94. It will be seen that the drum 94 thus has an oscillatory movement rotating through substantially one complete revolution in one direction and then rotating the same distance in the opposite direction alternately. 10 When the gear wheel 80 is on the inside, as shown in Fig. 1, its direction of rotation is such that the drum is rotating in the direction indicated by the arrow 120. At this time the clothes in the drum will be carried up some distance on the rear wall thereof, 15 so that the center of gravity of the drum and its load will be shifted far to the rear of the trunnions 71' and 67. Under some circumstances this might result in the force 20 applied from the gear 80 to the studs 81 having the effect of lifting the trunnions out of their seats. But at such a time the rod 83 passes above the trunnion 71' and positively holds it down in its seat. It will be 25 obvious from an inspection of Fig. 1 that when the gear 80 is on the outside of the circumferential series of studs 81, then the force will be applied in the opposite direction to these studs, thus tending to hold the trunnions down in their seats; moreover, at 30 this same time the rod 83 will be drawn to the right and its point will merely catch in one hole of the flange 70'. Thus, it will be seen that the rod 83 will not at such time prevent lifting the drum out of the tank. 35 When the drum is put back in the tank, the studs 81 will engage the gear wheel 80 on the outside and this will have the effect to swing the plate 75 aside so as to pull the rod 83 back enough to admit the trunnion 71' to its seat.

It will be seen that I have invented a strong, simple and durable all-metal washing machine. I desire to call particular attention to the manner in which the top frame comprising the members 46-47-44 and 52 is strengthened by the corner posts 15, as well as by the inside corner braces 32 and 30. As previously explained, the side top braces 46 and 47 abut against the front and rear top braces 44 and 52. One purpose of this arrangement is to hold the rear brace 52 rigidly against strains on the wringer 61. The top braces have an angular cross section which greatly increases their strength. As shown in the drawings, they are of greater depth at the corners so as to afford screw threaded sockets for the screws or stud bolts which pass through 55 from the corner posts 15. One purpose of having the flanges on the top edge braces is to cover the sharp rough edges of the sheet metal walls and the top ends of the corner posts.

60 The auxiliary cover 110 prevents the rapid

escape of steam when washing and yet as has been already explained, it permits drip water from the wringer 61 to drain down into the tank.

The corner braces 32 and 30 not only act 70 to stiffen the framework of the machine, but they have screw threaded sockets into which screws or stud bolts from the outside passing through the corner posts are introduced.

75 An inspection of Figs. 1 and 2 will show that when the washing drum reverses the direction of its rotation the door opening in the side thereof will be in front of the axis of the drum, that is, it will be directly at the left as viewed in Fig. 1, or directly at the right as viewed in Fig. 2. Thus it will be seen that at this time the two baffles 114 in the drum will be in the upper part thereof, that is, they will be substantially above a horizontal plane containing the axis of the drum. I mention these relations because they are employed in defining my invention with respect to said baffles in certain of the claims 90 which follow.

I claim:

1. In a cylinder washing machine, a sheet metal tank in which the cylinder is inclosed having a rectangular horizontal section, inside braces around the top edges of the side walls of the tank, inside angular corner braces, and angular corner posts fitted to the corners of the tank on the outside thereof, said posts being fastened through the tank walls to the top braces and to the inside corner braces, in combination with means mounted on said tank to rotatably support the cylinder therein.

2. In a washing machine, an oscillatory drum mounted to rotate on a horizontal axis, 105 mechanism adapted to rotate said drum alternately in opposite directions through substantially one complete rotation, two and only two longitudinal baffles within the drum, said baffles being so positioned that when the 110 reversal of the drum takes place they are both above a horizontal plane containing the axis of the drum.

3. In a cylinder washing machine, a sheet metal tank having an open rectangular top, 115 within which said cylinder is inclosed, flanges projecting inwardly from the inner faces of the side walls just below the top edges thereof, said flanges having their ends spaced from the front wall of the machine, 120 and a flat sheet metal cover adapted to rest upon said flanges or be slipped down within the tank in a vertical direction between the ends of the flanges and the front wall of the tank, in combination with means carried 125 by said tank for rotatably supporting the cylinder therein.

4. In a cylinder washing machine, a tank having a rectangular horizontal cross section and an open top, within which the cyl- 130

inder is inclosed, the opposite side walls of the tank each having an internal flange extending horizontally at a little distance below the top edge of the side wall and also 5 vertically at a little distance in from the front edge thereof, and a sheet metal cover adapted to rest upon said top flanges to close the tank or to lie in a vertical plane between the front wall and the opposed 10 flanges, in combination with means carried by said tank for rotatably supporting the cylinder therein.

5. In a cylinder washing machine, a sheet metal tank having a rectangular horizontal 15 section, within which the cylinder is inclosed, inside angle section corner braces fitting within the corners of the tank at the sides of one wall thereof, each of said braces having a flange spaced longitudinally from said 20 wall, and a cover adapted to lie in a vertical plane between said wall and the flanges, in combination with means secured to said tank for rotatably supporting the cylinder therein.

6. In a washing machine, a tank, a rotatable drum therein, means carried by said tank for rotatably supporting the drum, a cover hinged along the side of the drum, and fixed means to engage the free edge of the cover when the same is open and thereby 30 lock the same in a tangential direction and so prevent rotation of the drum.

7. In a washing machine, a tank, a rotatable drum therein, means carried by said tank for supporting the drum, a cover hinged along the side of the drum, an enlargement along the free edge of the cover, and a fixed socket adapted to receive said enlargement when the cover is open and thereby hold the drum against rotation.

40 8. In a washing machine, a tank, a rotatable drum therein, means supported by the tank upon which the drum is journaled, a flat cover for the tank adapted when open to stand vertically within the tank at one 45 side thereof, a socket on this cover, a cover for the drum hinged along one side thereof, and a member on the free edge of said last named cover adapted when it is open to lie within the said socket and thus hold the 50 drum against rotation.

9. In a washing machine, a tank, a drum

therein, means fixed to said tank for rotatably supporting the drum, a flat cover for the tank, means to hold said cover in a vertical position within the tank projecting a 55 little above the top thereof at one side of the tank, a socket on the upwardly projecting part of the cover, a door hinged along one side of the said drum, and means on the free edge of said door adapted to be engaged 60 by said socket.

10. In a cylinder washing machine, a sheet metal tank, within which the cylinder is inclosed, reinforcing braces along the top edges on the inside thereof, and a reinforcing inside corner brace having its upper end tapered, said tapered portion being overlapped by an oppositely inclined portion of the 65 said reinforcing braces, in combination with means carried by said tank for rotatably supporting the cylinder therein. 70

11. In a cylinder washing machine, a tank within which the cylinder is inclosed, a corner post having a right angle cross section, said corner post being jointed, one section thereof having a projecting tongue adapted to fit within the angle of the other section, and bolts connecting said tongue to said section, in combination with means mounted in said 75 tank for rotatably supporting the cylinder 80 therein.

12. In a cylinder washing machine, a tank, in which the cylinder is inclosed, corner posts at the corners of the tank extending below the bottom thereof, said posts having 85 joints at approximately the same level as the bottom of the tank, in combination with means mounted in said tank for rotatably supporting the cylinder therein.

13. In a washing machine, an oscillatory 90 drum, a retaining bar adapted to retain said drum in its bearings, gearing to drive said drum, and a shifting gear support for said gearing, said retaining bar being connected to the gear support. 95

In testimony whereof, I have subscribed my name.

HENRY WARD DARROW.
